(57) **CLAIM**

The ornamental design for a post guard portion, as shown and described.

DESCRIPTION

FIG. 1 is an upper perspective view of a post guard portion; FIG. 2 is a top plan view of the post guard portion of FIG. 1; FIG. 3 is a bottom plan view of the post guard portion of FIG. 1;

FIG. 4 is a front side elevation view of the post guard portion of FIG. 1;

FIG. 5 is a rear side elevation view of the post guard portion of FIG. 1;

FIG. 6 is a right side elevation view of the post guard portion of FIG. 1; and,

FIG. 7 is a left side elevation view of the post guard portion of FIG. 1.

The broken lines immediately adjacent the shaded areas represent the bounds of the claimed design while other broken lines are directed to environment and are for illustrative purposes only; features illustrated in broken lines form no part of the claimed design.

1 Claim, 4 Drawing Sheets
